By his Attorneys,

a Inventor
Major J. Robinson,

C. Brown & Co.

UNITED STATES PATENT OFFICE.

MAJOR J. ROBINSON, OF MARSHFIELD, WISCONSIN.

SHOE-BUCKLE.

SPECIFICATION forming part of Letters Patent No. 416,185, dated December 3, 1889.

Application filed July 23, 1889. Serial No. 318,358. (No model.)

To all whom it may concern:

Be it known that I, MAJOR J. ROBINSON, a citizen of the United States, residing at Marshfield, in the county of Wood and State 5 of Wisconsin, have invented a new and useful Shoe-Buckle, of which the following is a specification.

The invention relates to improvements in shoe-buckles.

10 The object of the present invention is to provide a shoe-buckle of simple and inexpensive construction adapted to be readily adjusted to accommodate the shoe to the wearer and capable of such adjustment without forcing some of its parts into the shoe, as is the case with a number of shoe-buckles in which springs are employed to hold the parts intact.

15 The invention consists in the construction and novel combination and arrangement of 20 parts hereinafter fully described, illustrated in the accompanying drawings, and pointed out in the claims hereto appended.

25 In the drawings, Figure 1 is a perspective view of a buckle constructed in accordance with the invention. Fig. 2 is a side elevation. Fig. 3 is a reverse plan view. Fig. 4 is a longitudinal sectional view. Fig. 5 is a detail view of the link. Fig. 6 is a transverse section.

30 Referring to the accompanying drawings by letter, A and A' designate two corresponding sections or plates, which are attached to the sides of the shoe by loops a, formed at the opposite ends of said plates.

35 The plates are curved longitudinally, and are approximately semi-cylindrical or curved in cross-section and readily fit upon each other, and are capable of sliding freely when a link B, connected to the section A', is lifted from 40 engagement with the section A. The sections are provided with lateral flanges a', which prevent them slipping apart, and the section A has a series of recesses a², which are shouldered in one direction and form 45 teeth which are designed to be engaged by the link B to hold the sections together.

The plates or sections A and A' are arranged within the link B, which is normally held in engagement with one of the recesses

a² by a spring C, which is secured to the lower 50 face of the section A', at the farther end thereof and within the curve of the sides, and has its free end engaging a projection b, formed upon the lower side of the link, which conforms to the configuration of the section 55 A'. The link B is provided in its sides with recesses b', which extend upward from the curved lower side a sufficient distance to receive the flanges a' of the section A, whereby the latter will be prevented leaving the sections a'. The sides of the link opposite the recesses b' are provided with bends b², which fit in notches a³, formed in lateral projections a⁴ at the side of the section A', a short distance forward of the free end of the spring C. 65

From the foregoing description and the accompanying drawings the construction, operation, and advantages of the invention will be readily seen.

I am aware that it is not broadly new to 70 provide a fastening device consisting of two sections sliding upon each other, one of the sections being provided with teeth and the other having a spring-actuated link adapted to engage the teeth of the other section and 75 hold the parts together. This prior construction was designed to be employed as a hamefastener, and, while embodying the same principle of operation, its arrangement and construction were such as to preclude its being adapted to form a shoe-buckle without 80 essential reconstruction.

Having described my invention, I claim—

1. A shoe-buckle comprising the similarly-shaped sections A and A', curved in cross-section and provided with lateral flanges a, one of said sections having a series of teeth and the other being provided with lateral projections a⁴, having notches, and the link having its lower edge curved and provided 90 with recesses b' in its sides near the lower ends thereof and fitting in said notches, substantially as described.

2. A shoe-buckle comprising the sections A A', curved in cross-section and sliding 95 upon each other and provided with lateral flanges a, one of the sections being provided with a series of teeth and the other having

notched projections a^4 , a spring secured to the end of the section A' and lying within its curved sides, and the link having its sides provided with bends b^2 and the recesses b' , and adapted to fit in the notches of said projections, substantially as described.

In testimony that I claim the foregoing as

my own I have hereto affixed my signature in presence of two witnesses.

MAJOR J. ROBINSON.

Witnesses:

FRANK A. CADY,
W. A. REED.
